Primary Examiner—Bernard Ansher**Assistant Examiner—Prabhakar Deshmukh****Attorney, Agent, or Firm—Kuhn and Muller****[57]****CLAIM**

The ornamental design for a toothbrush package blister, as shown and described.

DESCRIPTION

FIG. 1 is a front elevational view of a toothbrush package blister showing my new design;

FIG. 2 is a top plan view thereof;

FIG. 3 is a left side elevational view thereof; the right side elevational view being a mirror image thereof;

FIG. 4 is a bottom plan view thereof;

FIG. 5 is a rear elevational view thereof;

FIG. 6 is a fragmentary sectional elevational view thereof taken along line 6—6 of FIG. 5; and,

FIG. 7 is a fragmentary sectional elevational view thereof taken along line 7—7 of FIG. 5.

FIG. 1

FIG. 2

FIG. 3

FIG. 4

FIG. 5

FIG. 6

FIG. 7

UNITED STATES PATENT AND TRADEMARK OFFICE
CERTIFICATE OF CORRECTION

PATENT NO. : Des. 336,040
DATED : Jun. 1, 1993
INVENTOR(S) : Philippe Starck

It is certified that error appears in the above-identified patent and that said Letters Patent is hereby corrected as shown below:

On the Title page, under item [19]:

"Pahilippe" should be replaced by --Starck--.

[75] Inventor: "Starck Philippe" should be
replaced by --Philippe Starck--.

Signed and Sealed this

Twenty-first Day of September, 1993

Attest:

BRUCE LEHMAN
